(57) CLAIM

The ornamental design for a display screen or portion thereof with graphical user interface, as shown and described.

DESCRIPTION

The patent file contains at least one drawing executed in color. Copies of this patent with color drawings will be provided by the Office upon request and payment of the necessary fee.

The sole FIGURE is a front view of a display screen or portion thereof with graphical user interface showing our new design.

The outer perimeter shown in broken lines in the FIGURE depicts a display screen or portion thereof and forms no part of the claimed design.

Considerations for the Clinician¹

Most Important Pattern: Overnight, Morning, Afternoon

Medication

- For T1 patients, consider adjusting insulin.
- For T2 patients, consider taking insulin or sulfonylurea, consider adjusting medication
- For other T2 patients, consider adjusting medication or starting medication other than insulin or sulfonylurea

Lifestyle

Nights are often associated with high glucose variability. The following behaviors may contribute to glucose variability.

- Medication sometimes missed?
- Meals or snacks sometimes high in carbohydrates?

Occasional hypoglycemic occurrences under 54 mg/dL. See Daily View.

Glucose Patterns (14 Days)
